FIG. VII

INVENTOR:
HERMAN J. TRENKAMP
by his Atty. *Ernest A. Miller.*

UNITED STATES PATENT OFFICE.

HERMAN J. TRENKAMP, OF CLEVELAND, OHIO.

STOVE-OVEN ADAPTER.

Application filed May 9, 1919. Serial No. 295,886.

To all whom it may concern:

Be it known that I, HERMAN J. TRENKAMP, a citizen of the United States, residing at No. 9806 Quincy Ave., in the city of Cleveland, county of Cuyahoga, and State of Ohio, have invented a new and useful Improvement in Stove-Oven Adapters, of which the following is a specification, the principle of the invention being herein explained and the best mode in which I have contemplated applying that principle, so as to distinguish it from other inventions.

My invention relates to an improvement in stoves and is more particularly associated with the bake oven of a domestic stove.

The object of my invention is to make possible, both quickly and easily, the enlargement or restriction of the size of a bake oven according to requirement and to accomplish such object in a simple and economical manner.

It is a common expedient of domestic stove manufacture to partition a bake oven between a pair of independently controlled burners so that either division of the oven may be employed with a corresponding saving of fuel; or both divisions may be simultaneously employed so as to keep separated say, roasting meat and baking cakes. It is, however, not infrequently necessary to have available an abnormally large baking compartment for instance, when on festive occasions it is desired to roast a large fowl.

Accordingly, my invention comprehends the use of an oven partition capable of being shifted to a position against one wall of the oven or of being entirely withdrawn, and the further use in conjunction therewith of differently sized doors one of which carries a pair of others, the arrangement being such, that the larger door affords unrestricted access to the entire oven compartment whereas each of the other doors affords access to one of the oven divisions when the partition is in its functioning position, and the larger door is in its closed position.

The combination of a main door carrying other laterally adjacent doors is claimed in my Patent No. 1,355,868, issued October 19, 1920.

Adverting to the drawings:—

Fig. I is a front elevation of a stove embodying my invention showing all the doors closed.

Fig. II is a view corresponding to Fig. I showing the smaller doors open.

Fig. III is a view corresponding to Fig. I with the large door open.

Fig. IV is the same view as Fig. III 60 showing the partition in an altered position.

Fig. V is a vertical section taken on line V—V of Fig. III.

Fig. VI is a horizontal section taken on line VI—VI of Fig. I looking downwardly.

Fig. VII is a vertical section taken on line VII—VII of Fig. V.

Fig. VIII is an enlarged perspective view of the partition structure and also showing 70 the manner of its support upon the oven.

Fig. IX is a similarly enlarged vertical cross section of the lower portion of the partition structure.

The stove casing is supported on four 75 legs 1 and comprises a bottom 2, a front frame 3, side walls 4, a rear wall 5 having an opening above in communication with a stack 6 and a top 7. Supported in any suitable manner within the stove casing so as 80 to be spaced from the side walls 4 and the rear wall 5 is an oven compartment comprising a bottom 8, rear wall 9 and side walls 10. Inasmuch as the manner of so supporting an oven is old in the art and forms no 85 part of this invention its detailed description has been dispensed with. In consequence however, of such spaced relation of the oven compartment, an enveloping flue space 11 is provided. Carried by the under 90 surface of the bottom 8 are brackets 12 supporting each one end of burners 13 which have their opposite ends 14 supported in the front wall 3. The manner of igniting the burners 13 is of no interest to this application. Suffice it to say that each burner 13 is located underneath the middle of one lateral half of the oven compartment.

Affixed to the inside of each of the oven walls 10 is a pair of plates 15 provided with 100 a row of horizontal ledges 16. Secured along the median line of the oven bottom 8 are two pairs of juxtaposed angle clips 17 between which the base member 18 of a partition structure is adapted to be slid as is 105 clearly shown in Fig. VIII. The front and rear ends of the base 18 are bent upwardly at 19 and extending between such erectile ends is an upright web 20. The ends 19 are each provided with a pair of pins 21 located 110

on opposite sides of the web 20 respectively. Hinged each to a pair of pins 21 which are on the same side of the web 20 are partitions 22 provided with curled edges 23 as illustrated in Fig. IX. The purpose of so curling the edges of the partitions is to avoid possible injury to the hands and provide a dead air space therebetween. Arranged along the middle line of the top of the oven 10 in a direction from front to rear, as appears in Figs. IV and VII is an abutment 24 against which the free ends of the partitions 22 may be held by means of a binding clip 25 shown in Figs. III, V and VIII. Each of 15 the partitions 22 is provided on the further side with reference to the other partition with a row of horizontal ledges 26 which, when the partitions are erect, are similarly spaced and elevated as the ledges 16 so that 20 grills 27 may be caused to rest thereon in a substantially horizontal position as appears in Figs. II and III. When the partitions 22 are swung out of the way a longer grill 28 may similarly be caused to rest upon two 25 of the ledges 16 as appears in Fig. IV. It is to be understood that the distance between the hinges of the partitions and the free ends is enough less than one half of the distance between the walls 10 to permit of their free 30 ends being swung downwardly so as to clear all of the ledges 16 and assume their alternative non-functioning positions upon the bottom 8 as shown in Fig. IV. It is to be observed that the curled edges 23 of the partition 35 22 provide an air space therebetween when the partitions are set up. This has the advantage, when the oven is heated, of creating a rising current of heated air tending to hinder a commingling of the differing 40 fumes in the distant oven divisions.

Hinged to the front of the stove at two points 29 is a large door 30 of the same length that the stove is wide and adapted to swing downwardly to the position shown in 45 Fig. IV and thus expose the entire front open side of the oven compartment. It will be observed upon inspection of Fig. I that the door 30 has lateral ends 31 which are flush with the outermost edges of the casing 50 when the door is closed. A horizontal handle 32 is carried by the upper edge of the door. Hinged in turn at two points 33 on each of the lateral ends 30 is a pair of doors 34 which are adapted to swing in opposite 55 directions and to afford entry each to one half of the entire oven compartment. The doors 34 have vertically extending handles 35. As so constructed, it is manifest that each of the doors 34 may be opened independently of the door 30 and independently of each other; also, that whenever the large 60 door 30 is opened it carries both of the doors 34 down with it.

Ordinarily, either one half of the oven 65 compartment will suffice and likewise the

use of fuel from only one of the burners 13, in which event the partitions 22 will be left in their abutting upright position and only one of the doors 34 need be used. When however, it is desired to roast or bake something which requires the full dimensions of the oven the main door 30 is swung open the smaller grills 27 removed and after the spring clip 25 has been removed both partitions 22 permitted to fall to the positions 75 in which they appear in Fig. IV, after which the larger grill 28 may be inserted at any desired elevation. If the needs of any particular household more frequently require the use of the full size oven the entire partition structure including the base 18 may be removed until such time as it might be required. 80

My invention features a double accommodation in respect to oven size and facility 85 of access thereto, and at the same time halves in respect to fuel economy when less than the entire maximum available oven space is adequate. 90

I claim:—

1. A stove comprising the combination with a pair of laterally adjacent heating means of an oven carrying a partitioning structure comprising two parts movable relatively to each other and adapted in one 95 alternative inutile position to be in substantially the same plane and in operative position to be juxtaposed to divide said oven between said laterally adjacent heating means. 100

2. A stove comprising an oven having a displacable partition adapted to divide said oven into laterally adjacent sections, a large door affording entry to both sides of said partition and smaller doors carried by said large door and affording entry each to only one side of said partition. 105

3. A stove comprising an oven having a displaceable partition adapted in its operative position to be upright so as to divide 110 said oven into laterally adjacent sections, a door affording entry to both sections and a door carried by the first mentioned door and affording entry to only one of said oven sections. 115

4. A stove comprising an oven, a member adapted to form a partition thereacross, said member being so attached to the bottom of said oven as to allow it to assume an angular relation thereto to fulfil its function as a partition or to be moved into a position in a plane substantially parallel and close to the plane of said bottom of said oven, and a large door carrying a smaller door the large door being adapted to afford unrestricted access to said oven on both sides of said member and the small door being adapted to afford access to only one side of said member when in its partitioning position. 120

5. A stove comprising an oven, an up- 103

- right member adapted to form a partition thereacross, said member being so attached to one horizontal wall of said oven as to enable its assuming an angular relation there-
5 to to fulfil its function as an upright partition or to be moved into a position in a plane substantially parallel and close to the plane of the bottom of said oven, laterally disposed doors adapted to afford access to
10 the divisions of said oven on opposite lateral sides of said member respectively when the latter is in its partitioning position, and another door carrying both of said first mentioned doors and adapted to afford access
15 to the entire oven when said member is caused to occupy its alternative position.
6. A stove comprising an oven, and a pair of partition forming members hinged across said oven, each of said members being
20 adapted to rest upon the bottom of said oven and adapted in conjunction with each other to enclose an air space when in operative position.
7. A stove comprising an oven, a displace-
25 able member in said oven, and a pair of partition forming parts hinged to said member along closely adjacent substantially parallel lines and adapted to be moved apart or brought against each other.
- 30 8. A stove comprising an oven compartment, a member movably associated therewith and adapted to constitute an upright partition thereacross, a large door of substantially the same dimension as that of the
35 entire front of said oven and adapted when closed to extend across the near edge of said member when in its partitioning position and other laterally adjacent smaller doors carried by said large door and opening only
40 to the division spaces of said oven respectively the arrangement being such that when said member is not in its partitioning position said large door allows insertion of a utensil requiring the full size oven.
- 45 9. A stove comprising an oven, an upright structure including two parts movably attached to said oven and adapted to assume a partitioning position thereacross from front to rear, a clip for holding said parts
50 in one of their alternative positions, distinct heating means below said oven on different sides of said structure when in its partitioning position, and a pair of doors on opposite sides of said structure when in its parti-
55 tioning position.
10. A stove comprising an oven, ledges on the side walls thereof, an upright structure movably attached to said oven and adapted to assume a partitioning position there-
60 across, said structure including two sections having ledges projecting in opposite directions therefrom, means for holding said sections together, a pair of doors on opposite sides laterally of said structure when in
65 its partitioning position; and a grill adapt-
ed to rest upon one of said wall ledges and one of said partition ledges.
11. A stove comprising a pair of distinct fuel devices arranged side by side, an oven extending over both of said devices, a door
70 opening substantially the entire front of said oven, and other doors carried side by side on said first mentioned door and opening portions only of said oven over said distinct devices respectively.
75
12. A stove comprising a pair of distinct heating devices arranged side by side, an oven extending over both of said heating devices, a door opening substantially the entire front of said oven, and other doors carried side by side by the first mentioned door and opening portions only of said oven over said distinct heating devices respectively.
80
13. A stove comprising a pair of distinct heating devices arranged side by side, an oven extending over both of said heating devices, a door opening substantially the entire front of said oven, and adapted to move in one direction, and other doors carried side by side by the first mentioned door and opening portions only of said oven over said distinct heating devices respectively, and adapted each to move in relatively trans-
85 verse directions.
90
14. A stove comprising a pair of distinct heating devices arranged side by side, an oven extending over both of said heating devices, a door hinged to said stove and opening substantially the entire front of said oven, and adapted to swing in one direction, and other doors hinged in a side by side arrangement to the first mentioned door and opening portions only of said oven over said distinct heating devices respectively and adapted each to swing in relatively transverse direc-
95 tions.
100
15. A stove oven provided with a removable support adapted for insertion therein, and a partition hinged to said support.
105
16. A stove oven provided interiorly with a removable support, and a pair of partition forming parts mechanically connected to said support and adapted to assume alternative positions in said oven while so connected.
115
17. A stove comprising an oven, a displaceable structure adapted to partition said oven, a door opening substantially the entire front of said oven, and other laterally adjacent doors carried by said first mentioned door and opening partitioned end portions of said oven respectively.
120
18. A stove comprising a pair of distinct laterally adjacent fuel devices, an oven ex-
125 tends over both of said devices, a displaceable structure adapted to partition said oven, a door opening substantially the entire front of said oven, and other laterally adjacent doors carried by said first mentioned door and opening partitioned portions only of
130

said oven over said distinct devices respectively.

19. A stove comprising a pair of distinct heating devices arranged side by side, an oven 5 extending over both of said heating devices, a displaceable partition for said oven, a door opening substantially the entire front of said oven, and other doors carried by the first mentioned door in a side by side arrangement and opening portions only of said oven on opposite sides of said partition when in its operating position over said distinct heating devices respectively.

20. A stove comprising a pair of distinct heating devices arranged side by side, an oven 15 extending over both of said heating devices, a removable partition adapted for position between said heating devices, a door opening substantially the entire front of 20 said oven, and adapted to move in one direction, and other laterally adjacent doors carried by the first mentioned door and opening the partitioned portions only of said oven over said distinct heating devices respectively, and adapted each to move in relatively 25 transverse directions.

21. A stove comprising a pair of distinct heating devices arranged side by side, an oven 15 extending over both of said heating

devices, a displaceable partition for said 30 oven between said heating devices, a door hinged to said stove and opening substantially the entire front of said oven, and adapted to swing in one direction, and other laterally adjacent doors hinged to the first 35 mentioned door and affording access only to the partitioned portions of said oven over said distinct heating devices respectively and adapted each to swing in relatively 40 transverse directions.

22. A stove comprising an oven, guide parts carried interiorly of said oven, a member 45 slidably fitted between said guides and a pair of partition forming parts movably attached to said member.

23. A stove comprising an oven having end wall ledges, a support detachably connected across said oven in a direction substantially parallel with said end walls, a pair of partition forming parts movably attached to said support and adapted to be juxtaposed and ledges on said parts substantially parallel with said wall ledges and level therewith when said partition is in its 50 operative position.

Signed by me, this 29 day of April, 1919.

HERMAN J. TRENKAMP.
